(57) **CLAIM**

The ornamental design for an inverted bottle holder, as shown and described.

DESCRIPTION

FIG. 1 is a perspective view of the inverted bottle holder showing my design;

FIG. 2 is a front elevation view thereof;

FIG. 3 is a top plan view thereof;

FIG. 4 is a bottom plan view thereof; and,

FIG. 5 is a cross section view taken along line 5—5 of FIG. 3 showing a use thereof.

Rear, left and right elevations are identical to FIG. 2.

The broken line showing of the bottle in FIG. 1 and FIG. 5 are for illustrative purposes only and not forming a part of the claimed design.
